UNITED STATES PATENT OFFICE.

HARRY J. PERKINS, OF GRAND RAPIDS, MICHIGAN

REVERSIBLE ROTARY DRIVING DEVICE.

1,131,861.

Specification of Letters Patent. Patented Mar. 16, 1915.

Application filed April 4, 1913. Serial No. 758,781.

To all whom it may concern:

Be it known that I, HARRY J. PERKINS, a citizen of the United States, residing at Grand Rapids, in the county of Kent and State of Michigan, have invented new and useful Improvements in Reversible Rotary Driving Devices, of which the following is a specification.

My present invention relates to reversible rotary driving devices, and its object is to provide a device of that character in which the driving and the driven rotatable shafts may be coupled together to rotate as one shaft in the regular operation of the mechanism, *i. e.* when the driving is in the usual direction; and also, to provide such a device in which the principal operating parts may be readily removed from such shafts and replaced thereon by movement in the shafts' axial direction; and also, to provide a reversing gear-carrying cage which may be readily assembled with and removed from the other operative parts of the mechanism; and also, to provide other and subsidiary associated devices; and also to provide the foregoing or certain thereof in various combinations; and also, to provide a reversible rotary driving device improved in various particulars hereinafter appearing. These objects are attained by, and the invention finds a preferable embodiment in, the structure hereinafter described, and illustrated by the accompanying drawings in which:—

Figure 1 is a side view of my device: Fig. 2 is a forward end view thereof, one side being broken away: Fig. 3 is a vertical axial section of the same, certain parts being removed: Fig. 4 is a trans-axial sectional view of the same on a plane corresponding with line 4—4 of Fig. 3, and showing in face view, one of the frictional clutch disks: Fig. 5 is a like view of the device on a plane corresponding with line 5—5 of Fig. 3, and showing in face view one of the frictional clutch disks which coöperate with those like that shown in Fig. 4: Fig. 6 is a trans-axial sectional view of the reversing gear-carrying cage on a plane corresponding with line 6—6 of Fig. 7; and with line 6—6 of Fig. 3: Fig. 7 is an axial sectional view of the same on a plane corresponding with line 7—7 of Fig. 6: Fig. 8 is an axial sectional view of the principal operative parts of a variant form of my device, on a plane corresponding with line 8—8 of Fig. 9: Fig. 9 is a right-hand end view of the device shown in Fig. 8

with its head 58 removed: Fig. 10 is a detail top view of the drum's holding band's tightening device: Fig. 11 is a sectional view of the same on a plane corresponding with line 11—11 of Fig. 10: Fig. 12 is a detail top view of a variant form of such tightening device: and, Fig. 13 is a side view of a variant form of my device incased, certain parts being shown in vertical axial section.

My device is especially adapted for use in connection with the screw-propeller shafts of launches and other boats. In the construction shown, illustrating such a use, the device is supported by its lugs 1 resting on the engine bed on each side, as the beam 2 shown in Fig. 2. The driving shaft or engine shaft 3 is coupled, as hereinafter explained, with the alined driven shaft or propeller shaft 4 to rotate the same with it in the regular operation of the device, *i. e.*, when the driving is in the usual direction,—forward. In reversing the motion however, *i. e.* to "back" the boat, these shafts rotate in contrary directions as hereinafter explained. These ends are effected by the following mechanism: A hollow drum 5, concentric with and surrounding the shafts is adapted to rotate independently thereof, as on bushings 6: It is also adapted to couple by the following means the shafts together, that they may rotate as one: Keys 7 and keyways 8 on the interior wall of the drum, and resembling the teeth of an internal gear, interlock with corresponding keyways 9 and keys 10 of annular friction clutch disks 11 surrounding and concentric with the shafts: alternately disposed between these disks are coöperating clutch disks 12 having keyways 14 and keys 13 interlocking, in case of some such disks—as those to the right hand side of Fig. 3—with corresponding gear teeth 37 (and their intervals) carried by the driving shaft; and in case of the other such disks 12,—as those to the left of said figure—with similar teeth 15 (and their intervals) carried by the driven shaft. These clutch disks are frictionally clamped together side to side, in order to couple the shafts to each other, by suitable means, preferably a hand lever 16 stationarily fulcrumed as at 17 and having a suitable fork 18 engaging the grooved collar 19 slidable on the driven shaft: To this collar is pivoted as at 20 one arm 21 of a toggle whose other arm 22, pivotally connected at 23 to the arm 21, is fulcrumed at

24, in effect on the drum, *i. e.* on the drum's screw collar 25. The arm 22 is a lever having a cam 26 engaging a plunger 27 slideable on the drum and whose inner end engages the outmost disk 12. When the hand lever is pushed toward the right hand side of Fig. 1, it forces through the parts above described the disks and the gear-carrying cage 28 to the right of Figs. 1 and 2, and against the inner right-hand end wall of the drum 5, thus frictionally clamping such disks together, whereby their clutch operation is effected. The collar 25 is screw-threaded on the drum, as shown and is provided with a spring-pressed catch 29 adapted to enter a suitable orifice 30 in the end face of the drum, so that by turning the collar 25 the degree of the plunger's pressure may be regulated.

20 The engagement of the clutch disks being released, the rotary movement of the driven shaft is reversed by the following devices: A gear-carrying cage 28 is interposed between the clutch disks surrounding the driving shaft and those surrounding the driven shaft, as particularly shown in Fig. 3. This cage comprises parallel annular disk portions 31 spaced apart and connected by a web 34, and provided circumferentially with keys 32 and keyways 33 similar to those of the disks 11 and adapted to similarly interlock with the corresponding keyways 8 and keys 7 of the drum. On a spindle 100 extending between and carried by the disk portions 31 rotates the intermediate stepped gear 35 whose larger gear 36 meshes with and is driven by the gear teeth 37 of the driving shaft, and whose smaller gear 38 meshes with and drives the idler gear 39, pivoted on the cage's disk-portions, which gear meshes with the gear teeth 15 carried by the driven shaft. The drum is secured against rotary movement during the reverse driving of the propeller shaft by a frictionally holding band 40 stationarily fastened as to the engine bed plate, and tightened by suitable means, as a plunger 41 slideable on one end of the split band, as by a link 42 pivoted thereto and to the hand lever 16: In moving this plunger in the direction toward the left-hand of Fig. 1, it engages as by its shoulder 43 the lever arm 44 pivoted on the other end of the band, thus drawing the band's ends toward each other and clamping the drum by the band: the reverse motion of the plunger releases the arm 44 and loosens the band. It will be seen that by removing the drum's head 46 the disks and cage may be readily withdrawn, being slideable along the keys of the drum and the gear teeth of the shafts.

25 In the variant form of my invention shown in Figs. 8 and 9, there is an inner drum 47 keyed to the driven shaft and inclosing the disks which surround the driv-

ing shaft and the intermediate reversing gears 49 which are driven by the gear teeth 50 of the driving shaft and which drive the drum's internal gear 51: there is also an outer drum 48, inclosing the inner drum 73 and the disks surrounding the driven shaft. In the construction illustrated in Fig. 9 six of these reversing gears 49 are shown. When the clamping pressure is exerted on the plunger 27, the radially-extending flange 59 is clamped between the disks on the right-hand side thereof (which surround the driving shaft) and those on the left-hand side thereof (which surround the driven shaft), and thereby the shafts rotate in coupled relation as one.

30 In the variant form of my invention shown in Figs. 12 and 13, the means for tightening the drum's holding band comprise a pair of levers 52, having a common fulcrum, which engage lugs 53 at the ends of the split band: by drawing the plunger 54 toward the left-hand the lugs are pressed toward each other through the slotted arms 55 pivoted on the plunger. An adjusting screw 56 may be provided to regulate the action of the levers 52. The plunger 54 through suitable connecting parts 60 slides the collar 19 to engage or release the clutch disks. A suitable casing 57 may be provided.

35 Not confining myself to details of construction shown or described, I claim:

1. In a device of the character described, alined driving and driven shafts, a hollow drum having a concentric rotary movement relatively to the shafts, a cage within the drum and rotatable therewith, reversing gears carried by the cage, a clutch to clutch the cage with both the shafts, gears on the shafts meshing with the reversing gears carried by the cage, and means for holding the drum against rotation.

40 2. In a device of the character described, alined driving and driven shafts, a hollow drum having a concentric rotary movement relatively to the shafts, a cage within the drum and in longitudinally-removable keyed relation thereto, reversing gears carried by the cage, clutch members to clutch the cage with the shafts, gears on the shafts meshing with the reversing gears carried by the cage, and means for holding the drum against rotation.

45 3. In a device of the character described, alined driving and driven shafts, a hollow drum having a concentric rotary movement relatively to the shafts, a cage within the drum and in longitudinally-removable keyed relation thereto, reversing gears carried by the cage, a clutch member to clutch the cage and one shaft and in longitudinally-removable keyed relation to such shaft, a clutch member to clutch the cage and the other shaft and in longitudinally-

50 55 60 65 70 75 80 85 90 95 100 105 110 115 120 125 130

removable keyed relation to such other shaft, gears on the shafts meshing with the reversing gears carried by the cage, and means for holding the drum against rotation.

5 4. In a device of the character described, alined driving and driven shafts, a hollow drum having a concentric rotary movement relatively to the shafts, a cage within the drum rotatable therewith and having a longitudinal movement relatively to the shafts, reversing gears carried by the cage, clutch members carried by the shafts respectively and adapted to couple the shafts together by means of the cage, and means for moving one clutch member and the cage into clutching position with the other clutch member, gears on the shafts meshing with the reversing gears carried by the cage, and means for holding the drum against rotation.

5 5. In a device of the character described, alined driving and driven shafts, a hollow drum having a concentric rotary movement relatively to the shafts, a cage within the drum rotatable therewith, reversing gears carried by the cage, clutch members in

keyed relation alternately to the drum and to one shaft, to clutch the cage to such shaft, clutch members in keyed relation alternately to the drum and to the other shaft to clutch the cage to such other shaft, gears on the shafts meshing with the reversing gears carried by the cage, and means for holding the drum against rotation.

6. In a device of the character described, alined driving and driven shafts, a cage, reversing gears carried by the cage and axially parallel with the shafts, clutch mechanism comprising two clutch inmembers carried one by each shaft and coöperating with the cage to couple the shafts together, the relative movement of the clutch members being parallel to the shafts, gears on the shafts meshing with the reversing gears, and means for holding the cage against rotation.

In testimony whereof I have hereunto set my hand in presence of the subscribing witnesses.
